LAP

Anton Anderson, Chicago, Ill.

Application January 9, 1945, Serial No. 572,063

5 Claims. (Cl. 51—184.3)

This invention relates to laps intended principally for abrading or polishing walls of cylindrical holes, bores, or the like.

The objects of this invention are to provide a lap of this character which will be simple in construction and having novel expansible wearing portions constructed so that they will have a desired amount of inherent resiliency; to provide a lap which may be easily and readily adjusted to take up the wear, or for different sized holes; to provide a lap which will be durable and efficient in operation; to provide a lap having a cylindrical barrel with longitudinal slits arranged tangentially or at an angle to the radius of the cylinder whereby the segments between the slits will have a desired degree of resiliency; to provide a lap which will have a relatively fast abrading action when rotated in one direction and a smoothing or polishing action when rotated in the opposite direction; and to provide such other improvements in construction and advantages in operation as will appear from the following description.

In the accompanying drawing showing this invention,

Fig. 1 is a side view of the lap;

Fig. 2 is an enlarged longitudinal sectional view;

Fig. 3 is a cross section taken substantially on the line 3—3 of Fig. 2;

Fig. 4 is an enlarged cross section showing the operation of the lap when turned in the direction to cause rapid abrasion; and

Fig. 5 is a view similar to Fig. 4 showing the lap rotating in relatively opposite direction or in reversed position in the hole as for polishing purposes.

As shown in this drawing, the lap has a shank or stem portion 10 which is adapted to be held in a drill or other suitable machine tool for operating the same. This shank has a reduced threaded connection 11 which is engaged by a correspondingly threaded end 12 of the main cylindrical portion or barrel 13 of the lap. The ends of the barrel are provided with tapered or conical bores or recesses 14 and 15 which may conveniently be tapered at an 8° included angle. The inner ends of these bores terminate at a cross wall 16 which is pierced with a hole 17 leaving annular shoulders 18 extending inwardly at approximately the center of the barrel.

The barrel is provided with a plurality of substantially longitudinal cuts or slits 19 which extend to points adjacent to the threaded ends of the barrel. These slits may be milled, sawed, or

cut in any desired manner, and the arrangement thereof forms one of the novel features of this invention. Instead of being radially arranged, as has been heretofore proposed, these slits are at an angle to the radius or as shown in the present instance, are substantially tangential to the walls of the hole 17. These slits form expansible longitudinal segments 20, the outer surfaces of which provide the working areas of the lap. The positioning of the slits in this manner provides narrow lands 21 on each of the segments around the hole 17.

The segments or sides of the lap are adjusted by means of a tapered adjusting pin 22 which is adapted to enter the hole 17 and engage with the lands 21. This pin has an enlarged threaded portion 23 that engages with a correspondingly threaded end 24 of the barrel. This is preferably a left hand thread for reasons which will presently be described. The outer end 25 of the pin is flattened or otherwise shaped for engagement by a wrench or adjusting tool. When this pin is screwed inwardly, the tapered portion thereof will press against the several lands and spring or bow the several segments outwardly so that the central portions thereof will extend farthest from the center line or axis, thus providing the engaging surfaces 26 of the lap.

As shown in Fig. 5, the land or projection 21 of any one of the laps lies between radii x , y which pass outside of the working surface 26 of the corresponding lap, and consequently pressure exerted on the land by the pin is not exerted directly or radially against the working surface of the segment. Likewise pressure which is exerted on the working surface when the lap is in operation is not transmitted radially or directly against the pin. The land 21 may be considered as a fulcrum or bearing and when pressure is exerted against the outer or working surface of the segment, it will be resisted only by the twisting or torsional action of the segment, and therefore will have sufficient spring or resiliency to accomplish the desired results. The ends of the segments or longitudinal strips being relatively thin will assist in permitting this torsional or resilient movement. The greater thickness of the segments or engaging elements at the center will provide for more wear as it is in such portions that the principal amount of work is done and the wear is greatest in this area.

When the lap is to be used, the shank is inserted in the drill or machine tool in the usual manner and the adjusting pin is screwed in to

expand the segments to the desired diameter. The abrading material is applied in the usual manner and the lap is inserted in the hole as indicated at 27 in a work piece 28 which is to be lapped. If the lap is rotated in the direction indicated by the arrow in Fig. 4, the pressure on the segments will tend to swing the forward edges inwardly and thus permit more abrasive to enter the spaces between the segments and the walls of the hole. This operation serves for rapid abrasion or grinding. The adjusting pin 22, as above stated, is preferably provided with left hand thread 6 so that if the projecting tang 25 comes in contact with the bed of the drill, it will tend to unscrew or loosen the same, rather than to increase the pressure. If the movement of the lap is reversed as shown in Fig. 5, as by reversing the position of the lap in the drill, the leading edges of the segments which contact closely with the walls of the hole will tend to wipe away the abrasive and provides means for giving a smoothing action or smooth finish.

From this description, it will be seen that I provide a lap of simple construction having a single solid expanding pin acting against seats or bearings at substantially the middle of the lap whereby the abrading members may be uniformly expanded to provide a substantially barrel-shaped or curved working surface. Each segment has a cushion or resilient action which is inherent in the construction of the lap, and does not require additional tension members, springs, or the like. This cushioning is created by a twisting or rotating of the mid-portion of each lap segment with respect to the cylindrical uncut ends of the lap barrel.

My improved laps may be formed of any suitable material, but are preferably made of soft or mild steel such as commonly used for this purpose.

While I have shown a preferred form of my invention, it is my intention that the same may be modified as for different sizes or classes of work without departing from the scope of the invention as set forth in the following claims in which I claim:

1. A lap having a cylindrical barrel with an inwardly extending annular projection with a central hole therethrough, the walls of the barrel and said projection having a plurality of longitudinal slits substantially tangential to said hole forming working segments and also forming lands terminating at the circumference of said hole and means coacting with said lands to expand the segments.

2. A substantially cylindrical lap barrel having longitudinal slits which terminate at a dis-

tance from the ends of the barrel, to provide working segments, inwardly extending lands on said segments the inner ends of which terminate at the circumference of a central hole and, which are positioned circumferentially substantially beyond the radii embracing the outer face of the respective segment, whereby they are offset circumferentially with respect to the outer faces of the segments, said slits being arranged tangentially to said hole, and non-resilient adjusting means coacting with said lands for expanding the segments, the arrangement being such that the segments will have a torsionally resilient action when in use.

3. In a device of the character set forth, the combination of a stem, a lap barrel having threaded engagement with said stem, the walls of the barrel increasing in thickness towards the center thereof, an annular projection extending inwardly at the center and having a hole therethrough, slits arranged substantially tangentially to said hole and terminating short of the ends of the barrel and dividing the barrel into a plurality of working segments, a tapered adjusting pin having threaded engagement with the opposite end of the barrel and projecting through said hole and adapted to spread the working segments.

4. In combination, a stem, a lap barrel having threaded engagement with the stem and having conical bores extending inwardly from the ends thereof, an annular projection extending inwardly at substantially the center of the barrel and having a hole therethrough, said barrel having a plurality of longitudinal cuts through the walls thereof extending to points adjacent the ends of the barrel and extending through said projection, said cuts being arranged substantially tangentially to said hole, whereby lands are provided on each segment, a tapered adjusting pin having threaded engagement with the opposite end of the barrel and coacting with said lands for expanding the working segments, substantially as described.

5. A lap consisting of a barrel threaded at one end, for engagement with a stem, an annular projection extending inwardly intermediate the ends of the barrel and having a central hole therethrough, slits arranged substantially tangentially to said hole and terminating short of the ends of the barrel and dividing the barrel into a plurality of working segments, a tapered adjusting pin having threaded engagement with one end of the barrel and projecting through said hole for spreading the working segments.

ANTON ANDERSON.
